UNITED STATES PATENT OFFICE.

WILLIAM W. BENSON, OF PHILADELPHIA, PENNSYLVANIA.

SUPPORT FOR ELECTRIC CONDUCTORS.

No. 866,709.

Specification of Letters Patent.

Patented Sept. 24, 1907.

Application filed August 14, 1905. Serial No. 274,094.

To all whom it may concern:

Be it known that I, WILLIAM W. BENSON, a citizen of the United States, residing at Philadelphia, in the county of Philadelphia and State of Pennsylvania, have invented an Improved Support for Electric Conductors, of which the following is a specification.

This invention is a device, as a molding, for supporting electric conductors on ceilings and walls, and it comprises in its preferred construction, a strip of wood provided with one or more channels with side corrugations or irregularities and one or more grooves parallel to the channels forming one or more elastic members at the sides of the channels, whereby the channels are adapted to be sprung open to permit the insertion of a wire having an insulating covering and to automatically grip the wire when inserted.

The leading purposes are to provide a readily constructed, inexpensive and convenient conductor support in the form of a molding.

In the accompanying drawings, Figure 1 is a transverse sectional view representing a molding embodying the invention; Fig. 2 is a plan view and Fig. 3 is a transverse sectional view representing a modified form thereof.

In the drawing, the molding strip 1 has therein the longitudinal channels 2 with the irregular or corrugated sides 3. Adjacent to one or more of the sides of these channels is a groove or grooves 4 parallel thereto and of such character as to form flexible tongues 5 adapted to be sprung away from the channels to open them for the ready insertion of the wires 6 and to automatically grip the wires when seated. The wires, being thus held in place, are inclosed by securing the cap 7 on the seat 8.

Having described my invention, I claim:

1. A supporting device for an electric conductor having an open channel with side corrugations adapted for engaging and holding a conductor and a cap for covering said channel.

2. A supporting device for an electric conductor having an open channel with a corrugated side and a groove forming a flexible member adapted to be sprung to permit the insertion of a conductor in said channel.

In testimony whereof I have hereunto set my hand this tenth day of August 1905, in the presence of the subscribing witnesses.

WM. W. BENSON.
